U.S. Cl. D10—111

FIG. 1.

FIG. 3.

FIG. 2.

FIG. 4.

FIG. 1 is a front elevation illustrating a first embodiment of a traffic sign embodying my new design;

FIG. 2 is a front elevation of a second embodiment thereof;

FIG. 3 is a front elevation of a third embodiment thereof; and

FIG. 4 is a front elevation of a fourth embodiment thereof.

The back of each embodiment is plain. Each embodiment is thin and substantially planar.

The drawing is stippled and filled in to indicate contrast.

I claim:

The ornamental design for a traffic sign, substantially as shown and described.
